SPAT

Filed Dec. 29, 1927

UNITED STATES PATENT OFFICE.

HERBERT S. RAUH, OF NEW YORK, N. Y.

SPAT.

Application filed December 29, 1927. Serial No. 243,237.

This invention relates to spats or overgaiters such as are commonly worn to cover the ankle and a portion of the shoe, and the object of this invention is to produce a pair 5 of spats which will differ in no manner in appearance from those found on sale at this time, but which may be more quickly put on or taken off by the wearer with very much less trouble than the same operations call 10 for at present. This object is attained by providing the spats on the inside with a hookless sliding fastening, the other side or outer side having the usual button and buttonholes fastenings.

15 In the accompanying drawings the preferred form of this invention is illustrated, but it is not intended to limit the invention narrowly to the particular forms set forth. Of the drawings Fig. 1 represents a view 20 of the outer side of a spat showing the buttons and buttonholes fastenings. Fig. 2 is a like side view of the other or inner side of the spat showing the hookless fastening, its extent, and the manner in which it is covered 25 by suitable edge construction to leave the inner surface throughout smooth and even.

Like numbers are used to refer to the same part in the drawings and description.

Considering the drawings, a spat 1 of any 30 selected material, has the heel portion 2 and toe 3. It has a vertical division 4 at which the edges overlap in the usual manner, and which are secured by the buttons 5 and buttonholes 6. It is desired to call attention here to the 35 fact that the buttons may be changed in position without much trouble to adjust the size of the spats to the wearer.

The lower edge of the body portion 1 is provided with a strap 7 to pass under the 40 shoe, and the strap is secured by the buckle 8 or its equivalent. The materials of which the body 1 is made up customarily show stitches 9 around the edges.

Fig. 2 illustrates the inner side of the spat, 45 and it has a division 10, secured by a hookless sliding fastening 11 of the usual construction. The particular construction of the hookless fastening forms no part of this invention. It will be noted in Fig. 2 that the 50 hookless fastening continues downwardly into and for a part of the length of the strap 7. The strap is, therefore, correspondingly divided and the division thereof secured by the hookless fastening. An especially desirable and advantageous feature of this 55 invention is believed to be the construction

of the edge portions 12 and 13, which are made to cover the hookless fastening and to meet on a line. It will be noted that the edges or edge portions 14 and 15 at the top of the 60 division 10 are increased in extent to suitably receive and cover the slide 16 of the hookless fastening.

The operation is thought to be clearly discernible from the drawings and the foregoing. 65 Moving slide 16 down opens the spat and strap and affords ample and convenient room to place the same on the foot. Once adjusted, the slide is pulled up and the spats are secured to the foot with obviously much less 70 time and effort than would be demanded to unbutton and again button the outer division 4.

Having now described this invention and its mode of use, I claim:—

1. Spats or overgaiters comprising a body portion divided on opposite sides, one of the said divisions having buttons and buttonholes for securing the edges together, and the other division of the body portion having a 80 hookless sliding fastening, the lower edge of the said body portion being provided with a strap to pass under the shoe, the said strap being provided with a buckle, and the said hookless fastening continuing downwardly 85 into and for a part of the length of the said strap.

2. Spats or overgaiters comprising a body portion divided on opposite sides, one of the said divisions having buttons and buttonholes for securing the edges together, and the other division of the body portion having a hookless sliding fastening, the lower edge of the said body portion being provided with a strap to pass under the shoe, the said strap 95 having a buckle, and the last mentioned division of the body portion having edge portions constructed to lie externally over the said hookless fastening and to meet on a line whereby the external surface of the body of 100 the spat is smooth and even.

3. Spats or overgaiters comprising a body portion divided on opposite sides, one of the said divisions having buttons and buttonholes for securing the edges together, and the other division of the body portion having a hookless sliding fastening, the lower edge of the said body portion being provided with a strap to pass under the shoe, the said strap being provided with a buckle, the said 105 hookless fastening continuing downwardly 110 into and for a part of the length of the said

strap, and the last mentioned division of the body portion having edge portions constructed to lie externally over the said hookless fastening and to meet on a line whereby the 5 external surface of the body of the spat is smooth and even.

4. Spats or overgaiters comprising a body portion divided on opposite sides, one of the said divisions having buttons and button-
10 holes for securing the edges together, and the other division of the body portion hav-

ing a hookless sliding fastening, the said last mentioned division having edge portions constructed to lie over externally upon the said hookless fastening and to meet upon 15 a line, and the upper portions of the said edge portions being extended in width to receive and cover the slide of the said fastening whereby the external surface of the body of the spat is smooth and even. 20

In testimony whereof I affix my signature.
HERBERT S. RAUH.
